UNITED STATES PATENT OFFICE.

JOHN F. O'CONNOR, OF CHICAGO, ILLINOIS, ASSIGNOR TO WILLIAM H. MINER, OF CHICAGO, ILLINOIS.

RAILWAY DRAFT-RIGGING.

1,130,999.

Specification of Letters Patent.

Patented Mar. 9, 1915.

Application filed March 4, 1914. Serial No. 822,405.

To all whom it may concern:

Be it known that I, JOHN F. O'CONNOR, a citizen of the United States, residing at Chicago, in the county of Cook and State of Illinois, have invented a certain new and useful Improvement in Railway Draft-Rigging, of which the following is a full, clear, concise, and exact description, reference being had to the accompanying drawings, forming a part of this specification.

My invention relates to improvements in draft rigging for railway cars.

The object of my invention is to provide a draft rigging of efficient operation, and one adapted to easily start the car to which the same is applied.

In the drawings forming a part of this specification, Figure 1 is a plan view partly in horizontal section and partly in longitudinal section of a draft rigging embodying my invention; Fig. 2 is a side elevation partly in vertical longitudinal section on line 2—2 of Fig. 1; Fig. 3 is a cross-section on line 3—3 of Fig. 1.

Referring to the drawings, the numerals 4—4 indicate draft-sills or parts of the car-frame to which the draft rigging is applied. A draft-gear 5 is mounted between the sills in a manner hereinafter described. The said draft-gear comprises a shell 6 having an upper chamber 7 and a lower chamber 8, the said chambers being in vertical twin arrangement. Each of said chambers is open at its forward end 9, and closed at its rearward end by the preferably integral plate 10. Rearwardly of each chamber the shell is provided with preferably integral collars 11—11, each forming a rearwardly opening recess 12 to receive a set of preliminary springs 13. The said sets of preliminary springs each comprise preferably an outer spring 14 and an inner spring 15, the springs in each chamber 12 being seated at their forward ends against the adjacent plate 10, and being each rearwardly seated against the follower 16. The follower 16 comprises a plate 17 of sufficient dimensions to engage against the preliminary springs in each chamber 12, and is provided with a forwardly extended collar 18 adapted to surround the walls of the preliminary spring chambers 12. The shell 6 at its rearward end is provided with the shoulder 19, against which the collar is engaged upon full compressing movement of the preliminary springs 13. The follower 16 is connected with the draw-bar by draft arms 20—20 located on either side thereof, said arms being keyed to the follower 16 by a key 41, more particularly hereinafter described, said arms being also provided with elongated slots 21—21 at their forward ends by which the same are connected to the draw-bar 23 by coupler key 22. The rear portion only of the draw-bar is shown in the drawings. The said arms 20—20 are adapted to reciprocate in oppositely arranged grooves 24—24, which extend longitudinally in the cheek-plates 25—25, the said cheek-plates being attached to the draft-sills by the rivets 26—26, and having front stop-shoulders 27—27 and rear stop-shoulders 28—28. The coupler-key 22 also passes through longitudinally extended slots 29—29, passing through the forward ends of the cheek-plates and through the adjacent portions of the draft-sills 4—4. The slots 21—21 in the draft-arms 20 are suitably rearwardly extended to permit the rearward movement of the draw-bar without strain upon the coupler-key, the said key sliding therein in buffing movement and engaging against the forward ends of said slots in pulling movement of the rigging. Each chamber, 7 and 8 respectively, in the shell 6 contains the friction elements 31, comprising the friction shoes 32—32 and the wedge 33, each of said wedges being in engagement against the front follower 30, and each of said chambers also contains the spring elements 34 mounted between the rear end of the chamber and the friction elements. The spring elements 34 each comprise preferably an outer spring 35 and an inner spring 36. A connecting rod 37 is extended between the friction elements and the rear plate 10, effecting the closure of the rear end of each shell to hold the parts in each chamber in assembled position. The follower 16 is provided at either side with an elongated slot 38, the said slots 38 registering with the slots 39—39 through the draft-arms, and with the elongated slot 40 through the shell between the upper and lower chambers 7 and 8. A key 41 passes through the said alined slots and through slots 42—42, through the cheek-plates and adjacent portions of the draft-sills 4. The slots 42—42 are suitably forwardly extended to permit the forward travel of the key 41.

41 therein on forward movement of the draft-arms. The draft-gear is supported at its forward end by the tie-plate 43, which is suitably secured to the draft-sills 4 by the 5 bolts 44-44. At its rear end the draft-gear is supported by the key 41.

In normal position of the parts of the draft-rigging as illustrated in the drawings, the front follower engages against the front 10 stop-shoulders, and the rear follower 16 is in engagement against the rear stop-shoulders 28. On rearward movement of the draw-bar, the rear follower 16 remains in its normal position, the coupler-key 22 15 travels rearwardly in the adjacent slots through the draft-arms, cheek-plates and draft-sills. The front follower is forced rearwardly by the draw-bar and, the parts within the chambers 7 and 8 being in preferable 20 construction of higher compression-resisting capacity than the preliminary springs, the said springs are rearwardly compressed against the rear follower by the rearward movement of the shell 6. The key 25 41 during such movement remains stationary in reference to the draft-arms 20, and the rearward movement of the shell upon the key is permitted by the forward longitudinal extension of the slot 40. The preliminary 30 springs are compressed until the collar 18 of the follower 16 engages the shoulder 19 of the shell; thereupon the parts within the chambers 7 and 8 are compressed, the rearward movement of the friction elements 35 being resisted by the pressure of the spring elements 34 and the frictional action of the friction elements against the inner faces of the chambers 7 and 8.

It will be apparent that the initial action 40 of the parts within the chambers 7 and 8 may commence before the complete compression of the preliminary springs, but in preferable construction the preliminary springs capacity is such in relation to the 45 compression-resisting capacity of the parts within the chambers 7 and 8 that the initial movement of the shell will first compress the preliminary springs before any appreciable movement of the parts within

the chambers 7 and 8 takes place. On forward movement of the draw-bar, the coupler-key 22 engages against the forward ends of the slots 21 in the draft-arms 20, and the front follower 30 being in engagement against the front stop-shoulders 27, the rear 55 follower is drawn forwardly, compressing the preliminary springs until the forward movement of the follower 16 is stopped by the engagement of the collar 18 against the shoulders 19, whereupon on continued forward movement of the draw-bar, the parts within these chambers 7 and 8 are compressed.

I claim:—

1. In a draft rigging for railway cars, the 65 combination with a draw-bar, draft sills and stop members secured to the inner sides of the draft sills and provided with rear stop shoulders, of front and rear followers, a draft gear comprising a shell provided 70 with chambers in vertical twin arrangement therein, friction and spring elements in each of said chambers, and a transversely extending key, the rear follower being slidably connected to the shell and the key passing 75 through the shell and draft sills to slidably engage the rear follower with the shell, the rear follower abutting the rear stop shoulders under buff and in normal position of the parts. 80

2. In a draft rigging for railway cars, in combination, draft sills, stop members secured thereto and provided with rear stop shoulders, a draw-bar, links connected with said draw-bar, two casings longitudinally 85 movable with respect to each other, a preliminary compression spring interposed between said casings, a key connecting said links and passing through slots in both of said casings, and friction mechanism located 90 in one of said casings, the rear one of said casings abutting the rear stop shoulders in normal position of the parts.

JOHN F. O'CONNOR.
